Herbert E. Twomley, Riverside, Calif., assignor,
by mesne assignments, to Food Machinery Cor-
poration, a corporation of Delaware

Application August 10, 1935, Serial No. 35,665

10 Claims. (Cl. 1—10)

My invention relates to presses, and has particular reference to box presses employed to compress contents within a box and to apply lids thereto.

In the packaging of fruits, vegetables, and similar commodities, it is the common practice to fill a box or crate with the desired contents, placing a sufficient quantity of the contents within the box to extend a considerable distance above the upper edges of the walls of the box and then to apply lids or covers to the boxes by pressing the covers down upon the extending overpacked contents, compressing the contents down into the box, and then securing the covers in place thereon. These machines usually comprise a box-supporting table upon which boxes filled with their contents may rest immediately below lid-pressing elements which are adapted to engage and press the lids upon the boxes, either when the box-supporting table is lifted toward the lid-pressing mechanism or when the lid-pressing mechanism is lowered toward the supporting table. In certain types of these machines, and in handling certain types of commodities, it is more convenient to lift the box-supporting table toward a relatively stationarily disposed lid-pressing mechanism to accomplish the lid-pressing operations. It is also desirable that when the lid is compressed down upon the box it should be permanently secured to the box as by means of nails or other devices which may be applied while the pressing operation continues.

In such instances where the box-supporting table is lifted toward the compressing or nailing elements, it is essential that the table and the lid-pressing mechanism be normally spaced a sufficient distance apart to permit ready ingress into the machine of the boxes with their protruding contents, so that the amount of movement provided for the table must be relatively great in order to permit a relatively great compression of the contents of the box. Moreover, it is also essential that when the table has been elevated to compress the contents and to press the lids down upon the boxes, sufficient resistance must be provided to oppose the forces which may be employed to drive nails or other securing members through the covers and into the boxes.

To provide this relatively great amount of movement of the box-supporting table, and to provide the necessary resistance for the nailing or securing operations, various forms of drive mechanisms have been employed, such as hydraulic pistons and cylinders, using relatively

non-compressible fluids, positive mechanical lifting mechanisms, such as screw jacks, chain lifts, and similar mechanisms. However it is frequently desirable to employ an air cylinder and piston mechanism for this purpose, but air, being relatively compressible, requires the employment of an extremely large volume of air at relatively high pressure to produce the long distance of travel and the required resistance to the downward thrust of the nailing or lid-securing mechanism, rendering it necessary to provide large tanks for the storage of air and compressors of relatively great capacity, which renders the machine employing this type of drive expensive.

It is an object of my invention to provide a system of transmission between a driving element, such as a fluid operated piston, and a driven element, such as a box-supporting table, wherein a portion of the movement of the driving element causes the driven element to be moved through a relatively great distance, and then the further movement of the driving element moves the driven element directly, and at the same rate as the driving element.

Another object of the invention is to provide a fluid lift of the character set forth in the preceding paragraph, wherein a fluid driven piston of relatively short stroke is employed and in which one or more levers are employed between the piston and the box-supporting table to produce a relatively long travel of the table from the short travel of the piston mechanism.

Another object of the invention is to provide a relatively simple control mechanism which may be employed for a fluid lifting means of the character set forth.

Other objects and advantages will be apparent from a study of the following specifications, read in connection with the accompanying drawings, wherein

Figure 1 is a side elevational view of a lidding machine constructed in accordance with my invention;

Figure 2 is a detail front elevational view of a box-supporting table and lifting mechanism embodying my invention;

Figure 3 is a sectional view, taken along line III—III of Fig. 2;

Figure 4 is a sectional view, taken along line IV—IV of Fig. 2; and

Figure 5 is a detail sectional view taken along line V—V of Fig. 2.

Referring to the drawings, I have illustrated my invention as embodied in a machine for pressing and nailing lids to overfilled boxes or crates

in which the machine includes a pair of side frames 1 and 2 interconnected by suitable cross-bracing 3 and 4. Each of the side frames is provided with a vertically extending upright guide 5 between the upper ends of which is suspended lid-pressing mechanism indicated by the reference character 6, and nailing mechanism indicated by the reference character 7.

As will be understood by those skilled in the art, the lid-pressing mechanism consists essentially in a frame-like structure having a pair of forwardly extending bracket arms 8, one on each side of the machine, spaced from each other by a distance just slightly less than the distance 15 between the ends of the boxes upon which the machine is to operate. The bracket arms 8 are each provided with a plurality of nail chucks 9, the lower ends of which are adapted to engage the extreme ends of a cover 10 to press the cover 20 ends into contact with the ends of a box 11 when the box and bracket arms 8 are moved toward each other. If desired, suitable end tuckers 12 may be supported upon the bracket arms 8 to extend over the edges of the box to engage any 25 overhanging contents and press the same inwardly of the box immediately prior to the pressing of the cover ends into contact with the box ends.

In order to perform the pressing operations, I provide an elevating platform constructed as a 30 box-supporting table 13 consisting essentially in a rectangular frame embodying side rails 14 and 15 interconnected near their ends by a pair of cross bars 16, while a cross bar 17 interconnects the side rail members near their middle. A plurality of rollers 18 are mounted between the side rails 14 and 15 to form the box-supporting table into a sectional roller type conveyor over which boxes may be readily drawn into the machine and moved outwardly of the machine.

40 The box-supporting table illustrated herein is adapted to move up and down and is guided by means of a pair of guide posts 19 and 20 at opposite ends thereof, the guide posts being secured rigidly to and depending from the end cross bars 16 of the box-supporting table. The side frame 1 of the machine is provided with a pair of inwardly extending vertical bearing members 21 through which the guide post 19 operates, while the side frame 2 is similarly provided with 50 a pair of vertical bearing members 22 to guide the post 20 in its vertical movement.

In order to accomplish the lifting and lowering operations of the box-supporting table 13, I provide driving elements constituted herein as 55 an air cylinder and piston mechanism comprising a relatively short cylinder 23 suitably supported upon the frame of the machine, as upon the cross-brace 3 thereof. The cylinder 23 may be formed of a section of cylindrical tubing having a lower head 24 and an upper head 25 clamped thereon by means of suitable tie-bolts 26. The upper head 25 is provided with an opening 60 through which extends a piston rod 28 connecting with a piston 29 movable vertically within the cylinder 23. Thus by passing air under pressure into the cylinder beneath the piston 29, the piston and its rod 28 will be raised, while escape of the air from beneath the piston will cause the piston to be lowered. Air may be introduced 65 and exhausted from the cylinder 23 in any suitable manner, though I prefer to provide the lower head 24 with an inlet port 30 to which may be connected a suitable supply pipe 31 by which air is admitted beneath the piston, while an exhaust port 32, connected to an exhaust pipe 33, may

be provided to permit air to pass out of the cylinder.

By referring particularly to Fig. 1, it will be observed that the height of the cylinder 23 is relatively small as compared to the distance of travel (indicated by the legend "travel") through which the box-supporting table 13 must be elevated in order to bring the box against the cover 10 and to press the ends of the cover 10 into contact with the ends of the box. In order to 10 permit a relatively short stroke of the piston 29 to accomplish the relatively long travel of the box-supporting table, I connect the piston rod 28 with the box-supporting table by means of links and levers which will multiply the amount 15 of movement, during a part of the stroke of the piston and which will constitute a direct drive during the later portion of the piston stroke.

Referring particularly to Figs. 3 and 4, it will be observed that the upper end of the piston rod 20 28 is formed with a reduced section 34 to which is secured a cross head 35, each end of which is bifurcated, as indicated at 36, to receive a pair of levers 37 pivoted to the cross head 35 as by means of a pin 38, while the opposite end 25 of the cross head 35 supports a similar pair of levers 39 pivoted thereto by means of a pin 40.

The levers 37 are interconnected at their inner ends by means of pins 41 and levers 39 are interconnected at their inner ends by means of pins 42, and upon each of the pins 41 and 42 there is mounted a roller 44 and 45, respectively. The roller 44 is aligned with and is engaged in a notch 46 formed upon the edge of a vertically extending guide means or plate 47, which plate is rigidly secured to the uppermost head 25 of the cylinder 23 so that upon elevation of the piston 29 and its cross head 35 the levers 37 will be fulcrumed around their roller 44 which is initially maintained against upward movement by 40 its reception in the notch 46.

The outer ends of the levers 37 are interconnected by means of a pin 48 which constitutes a pivotal connection with a link 49, the opposite end of which is pivoted as at 50 to a lug 51 formed 45 upon and extending down below the center cross bar 17 of the box-supporting table structure. In like manner the roller 45 for the levers 39 is engaged in a slot 52 in a second vertically extending plate 53, which, like the plate 47 is rigidly 50 mounted upon the upper head 25 of the cylinder 23. Likewise the outer ends of the levers 39 are connected by means of a pin 54 to one end of a link 55 the opposite end of which is connected as at 56 to a downwardly depending lug 57 formed 55 upon the center cross bar 17 of the box-supporting table structure. In order to brace the upper ends of the guide plates 47 and 53, I may interconnect them by means of a bar 58, the plates 47 and 53 being spaced apart to provide an elongated slot 59 through which the central portion of the cross head 35 may move vertically.

It will be observed that the point of application of lifting force to the levers 37, namely at the pin 38, is closer to the fulcrumed point of 65 this lever than is the connection 48 between the levers 37 and the link 49. Thus a relatively short upward thrust on the cross head 35 will cause a relatively great lifting movement of the box-supporting table 13.

Referring particularly to Fig. 3, it will be observed that I have illustrated therein the position of the piston, levers 37-39, links 49 and 55 and the box-supporting table 13 in their lowermost position in full lines, while in dotted lines 75

I have illustrated the extreme elevated position of the box-supporting table 13 with the intermediate positions of the links and levers illustrated in broken lines. From an inspection of this figure, it will be apparent that the linkage between the piston 29 and the table 13 is such that the initial upward movement of the table operates through the greatest leverage ratios to swing the levers 37 and 39 through an arc slightly less than 180°. As the piston 29 continues to rise in its cylinder, the upward force transmitted through the pins 38 and 40 will cause the toggle links formed by the levers 37 and links 49 and by levers 39 and links 55, respectively, to be substantially straightened out, which will cause the rollers 44 and 45 to be withdrawn from their notches 46 and 52, respectively. Continued upward movement of the piston 29 will raise the pins 38 and 40 additionally, thus causing the now straightened toggle links to be lifted bodily upwardly, the rollers 44 and 45 riding upon the exterior edges of the plates 47 and 53. Thus while a short initial travel of the piston 29 is employed to rapidly raise the table 13 through its levers and links, this action occurs at a time when the only resistance to the lifting of the table 13 is the weight of the box and its contents, while the last portion of the travel of the table 13 is additionally resisted by the pressing of the cover down upon the box, and this is accomplished by a direct upward thrust of the piston 29 transmitted directly through the straightened toggle links, thus applying the full lifting power of the piston to accomplish this thrust.

By the employment of the structure just described, it will be apparent that a relatively small volume of air is required to accomplish the lifting of the table 13, while the application of the force of such small volume of air is distributed throughout the cycle of operations so that the maximum power is delivered at the time the maximum resistance is encountered. This is of unusual advantage when, (as is usual) the amount of space which must be allotted to a tank or reservoir for compressed air is limited, each operation of the lifting of the table requiring but a relatively small volume of air and thus the capacity of the tank or reservoir may be relatively small.

Referring particularly to Figures 1, 2 and 4, I have illustrated the controlling apparatus by which the lifting and lowering operations of the table 13 may be accomplished by an operator of the machine, this controlling apparatus including essentially a pair of valves, intake control valve 60 interposed in the pipe 31 between the source of supply or tank and the cylinder 23 and an exhaust valve 61 interposed in the pipe 33 between the cylinder 23 and an exhaust outlet 62. The intake valve 60 may be readily controlled by means of a foot pedal 63, pivoted as at 64 upon an upstanding lug 65 formed upon the base 66 of the machine, extending immediately above the valve 60. The valve 60, being of the normal closed type, will be opened only when the pedal 63 is actuated by the operator of the machine and at that time will admit air from the source of supply into the cylinder 23.

If, during the ascent of the box-supporting table 13 it appears that the contents of the box are likely to be crushed during the pressing operations, or that the cover is not properly aligned or adjusted relative to the box, the table 13 may be stopped at any position by the mere release 75 of the pedal 63. The table is held in the elevated

position upon the release of the pedal 63 because the exhaust valve 61 in the exhaust line 33 is normally closed and will prevent the escape of air from the cylinder 23 until this valve 61 is opened.

If it is desired to lower the box-supporting table 13 prior to the completion of the nailing operation, the valve 61 may be opened by means of an auxiliary foot pedal 67 rigidly secured to a shaft 68 extending across the machine and journaled in suitable bearing brackets 69 and 70 at opposite sides of the machine. Rigidly secured upon the shaft 68 near either of its ends are levers 71 and 72, respectively, interconnected at their outer ends by means of a rod 73, which rod is secured to the operating element of the valve 61. Thus upon depression of the pedal 67, the valve 61 will be opened and the air which has been admitted into the cylinder 23 under the piston will be exhausted, permitting the piston to be lowered and returning the box-supporting table to its lowermost position.

If, however, it appears that the condition of the contents of the box and cover are such that the pressing and lidding operations may be completed, the operator continues to hold the pedal 63 depressed until the box has been elevated against the nail chucks or other lid-engaging elements to spring the cover ends down into contact with the box ends. Since the bracket arms 8 are rigidly secured to the frame of the machine, it will be apparent that the full force of the compressed air admitted to the cylinder 23 may be employed until forward movement of the table 13 is stopped by the positive resistance exerted by the lid-pressing mechanism.

The cover is now in position to be nailed or otherwise secured upon the box and the nailing operations may now occur.

By referring particularly to Figure 1 it will be observed that the nailing mechanism for one end of the machine includes a forwardly extending bracket 75, one end of which is slidably mounted upon the bracket 8, as by means of a slide bearing 76, while the opposite end of the bracket 75 is connected as at 77 and 78 to a cross head structure 79 extending between the uprights 5 on opposite sides of the machine. It will be understood by those skilled in the art that at the opposite end of the machine a similar bracket 75 will extend forwardly of the machine being suitably slidably supported upon the bracket 8 at that end of the machine, the two brackets 75 and the frame 79 constituting a nailing frame mechanism which may be reciprocated vertically relative to the brackets 8 and the nail chucks 9 by means of a connecting rod 80, one end of which is coupled to the frame 79 and the other end of which is coupled to a crankpin 81 extending forwardly from a wheel 82 adapted to be rotated by means of a motor 83. In order to permit the operator of the machine to control the movement of the wheel 82 to cause the nailing mechanism to move downwardly toward the box and to return to its uppermost position as illustrated in Fig. 1, the motor 83 is coupled to the wheel 82 through suitable reduction gearing 84 and a clutch 85 which clutch is adapted to be engaged by the depression of a nailing pedal 86 pivoted as at 87 upon the frame of the machine and connected by means of a link 88 to a clutch operating yoke 89.

As will be understood by those skilled in the art, the clutch pedal 86 may be provided with suitable cam-actuated mechanism for causing the

clutch 85 to be disengaged at the end of one revolution of the wheel 82 so as to prevent a second nailing operation should the operator inadvertently maintain the pedal 86 depressed after the first nailing operation takes place. This being a common practice in the art, it is not believed essential to illustrate or describe the same herein.

Each of the brackets 75 of the nailing mechanism is provided with a plurality of downwardly depending nail punches 90 extending into and through the nail chucks 9 so that when the nailing mechanism and the arms 75 are moved downwardly relative to the brackets 8 and nail chucks 9, the nail punches 90 will drive nails through the nail chucks, through the cover ends and into the ends of the box 11, thus securing the cover in place upon the box.

Since the box-supporting table 13 is held in its elevated position until the actuation or opening 20 of the exhaust valve 61, I prefer to provide a mechanism which will automatically open this valve at the completion of the nailing operation to automatically return the box-supporting table 13 to its lowermost position. This may be readily accomplished by providing a cam surface 91 on the wheel 82 so disposed relative to the crankpin 81 that at the termination of the nailing operation the cam 91 will engage a rod 92 and move the same forwardly. The rod 92 may be provided with a tailpiece or other coupling means 93 to engage the rod 73 to press the same forwardly in the same manner as though the release pedal 67 had been actuated, thus opening the valve 61. By properly proportioning the length of the cam 35 surface 91 the valve 61 will be held open a sufficient length of time to permit all of the air to be exhausted from the cylinder 23, it being preferable to form the exhaust pipe 33 of relatively large diameter so that the exhausting of the air may 40 occur with great rapidity.

In order, however, to prevent the too rapid descent of the table 13, I prefer to provide a dash pot or oil check mechanism governing the speed of descent of this table 13, which may comprise a cylinder 95 having a suitable piston 96, the piston rod 97 of which is provided with a yoke 98 bearing a crosspin 99. The box-supporting table 13 is provided with a U-shaped yoke 100 surrounding the pin 99 and preferably being of an elongated character to provide an elongated slot 101 by which the box-supporting table is permitted both lifting and lowering movements through a relatively short distance before positive connection is made between the dashpot 95. Thus the initial upward movement and the initial 55 downward movement of the table 13 will be relatively free, while the latter portions of the movement of the box-supporting table will be restrained by the oil check dashpot mechanism.

The operation of the machine through a complete cycle is as follows:

Assume that the machine is in the position shown in Fig. 1 in which the table 13 is in lowermost position ready to receive a box and the 60 pedals 63, 67 and 68 are in normal upper position. Under these conditions the valves controlling fluid flow into and out of the cylinder 23 are closed and the clutch 85 is disengaged. Let it be assumed that the motor 83 is in operation. Assume also that a box 11 is in position on the 65 table 13 and that a box lid 10 is retained in the lid-pressing mechanism 6.

The operator then depresses the pedal 63 which opens the intake valve 60 and admits pressure fluid through the line 31 into the bottom of the

cylinder 23, thereby raising the piston 29, the piston rod 28 and the cross head 36. The movement of the cross head 36 and the pins 38 and 40 attached thereto first rotates the levers 37 and 39 about the rollers 44 and 45, respectively as fulcrums until the rollers 44 and 45 are carried out of the slots 46 and 52 in the frame members 47 and 53 after which the levers 37 and 39 are moved directly upwardly, all as previously described, to first lift the table 13 and the box 11 thereon very rapidly into close proximity to the lid-pressing mechanism 6 and then move it slowly but with great force through the final distance to press the box into firm engagement with the lid.

Should it appear during the upward movement 15 of the table 13 that the contents of the box might be crushed or that the cover is not properly aligned, or that anything else is wrong, the operator can immediately stop the upward movement by releasing the pedal 63 to cut off the fluid 20 supply to the cylinder 23. If the operator should find it necessary to lower the table he can do so by stepping on the pedal 67 thereby opening exhaust valve 61 and releasing fluid from the cylinder 23 to permit downward movement of the 25 piston 29 and the table.

However, if everything appears to be in order the operator maintains pedal 63 depressed until the box 11 is carried up into firm engagement with the lid 10 after which the operator actuates the 30 nailing mechanism by depressing the pedal 86 which engages the clutch 85, thereby causing the motor 83 to rotate the wheel 82 through a revolution to move the nailing mechanism carrying the nail punches 90 downwardly to drive the nails 35 through the lid and into the box, the nail punches then returning upwardly to normal position. As previously indicated, it is customary to provide a suitable cam-actuated mechanism for causing the clutch 85 to be automatically disengaged at the end of one revolution of the wheel 82 so as to prevent a second nailing operation should the operator inadvertently maintain the 40 pedal 86 after the first nailing operation takes place. Such a mechanism may be provided in the present machine, but has not been specifically illustrated because such mechanisms are well-known in the art and specifically do not constitute a part of the present invention. It may therefore be assumed that either by reason of an 45 automatic release mechanism of the type referred to or by the release of pedal 86 at the proper time by the operator, the wheel 83 is stopped at the conclusion of one revolution.

During the final movement of the wheel 82 in completing its revolution, the cam 91 thereon actuates the push rod 92 which, acting through the coupling means 93, presses the rod 73 forwardly in the same manner as though the release pedal 67 had been actuated, thereby automatically 50 opening the exhaust valve 61 to permit exhaust of the air from the cylinder 23 so that the table 13 and the lidded box thereon are automatically lowered into the position shown in Fig. 1. During this operation excessively rapid downward movement of the table is prevented by the damping action of the dash pot mechanism comprising the cylinder 95 having the piston 96 connected through piston rod 97, yoke 98 and cross pin 99 to the table. By virtue of the fact that the pin 99 has substantial free movement in the slot 101 in the yoke 100, the table drops rapidly at first 55 without restraint from the piston 96 until the pin 99 reaches the lower end of the slot 101, but after that the piston is forced to move and the fric- 60

tional resistance to movement of the piston offered by the fluid in the cylinder 25 controls and limits the rate of movement of the table.

While I have illustrated the pressing apparatus 5 as a box-supporting table and a fluid cylinder and piston mechanism, it will be understood by those skilled in the art that the transmission system for causing rectilinear movement of the table 13 by a shorter rectilinear movement of the piston 10 29 is well adapted to the transmission of rectilinear movement from any driving member having rectilinear movement to any driven member having linear movement requiring a greater rate of travel per unit of distance of movement of the 15 driving member for a portion of the drive and requiring a substantially direct drive of great force during other portions of the movement of the driving member.

While I have shown and described the preferred embodiment of my invention, I do not wish to be limited to any of the details of construction shown herein, except as defined in the appended claims.

I claim:

25 1. In a power transmission, a driving member movable through a predetermined distance, a driven member, a lever, means connecting one end of said lever to said driven member, means connecting an intermediate point of said lever to 30 said driving member, guide means engaging the opposite end of said lever to form a fulcrum about which said lever is rotated during a portion of the movement of said driving member and forming a slide bearing along which said lever slides 35 during the remaining portion of the movement of said driving member.

2. In a power transmission, a driving member movable through a predetermined distance, a driven member, a lever, means connecting one end of said lever to said driven member, means connecting an intermediate point of said lever to said driving member, guide means engaging the opposite end of said lever and having a guide surface thereon including a portion forming a 40 slide bearing along which said lever may move during a portion of the movement of said driving member to transmit force from said driving member directly to said driven member and having a recess receiving said end of said lever to 45 form a fulcrum about which said lever rotates during another portion of the movement of said driving member to cause said driven member to move at a greater rate than said driving member during said other portion of the movement of 50 said driving member.

55 3. In a power transmission, a driving member movable in a straight path through a predetermined distance, a driven member movable rectilinearly, a lever, means connecting one end of 60 said lever to said driven member, means connecting an intermediate point of said lever to said driving member, guide means forming a bearing surface for the opposite end of said lever, including a recess for receiving said end of said 65 lever to form a fulcrum about which said lever rotates during a portion of the movement of said driving member to move said driven member at a greater rate than said driving member, and a slide bearing surface communicating with said 70 recess to form a track along which said lever may move during the remaining portion of the movement of said driving member to cause said driven member to move at the same rate, transmitting power direct from 75 said driving member to said driven member.

4. In a power transmission, a driving member movable in a straight path through a predetermined distance, a driven member movable rectilinearly, a lever, means connecting one end of said lever to said driven member, means connecting an intermediate point of said lever to said driving member, guide means forming a bearing surface for the opposite end of said lever including a recess for receiving the end of said lever to form a fulcrum about which said lever rotates during the first portion of movement of said driving member to thereby cause power to be transmitted from said driving member to said driven member through leverage action of said lever and causing said driven member to move at a greater rate than said driven member, and having a trackway extending from said recess along which said lever may slide during the later portion of the movement of said driving member to thereby transmit driving force from said driving member to said driven member directly, causing said driving member and said driven member to move at the same rate.

5. In a power lift, a base, a cylinder secured to said base, a piston reciprocable in said cylinder, a platform, a lever, means connecting one end of said lever to said platform, means connecting an intermediate point of said lever to said piston, guide means stationarily mounted relative to said cylinder for engaging the opposite end of said lever, forming a fulcrum about which said lever rotates during a portion of the movement of said piston, and forming a slide bearing along which said lever slides during the remaining portions of the movement of said piston.

6. In a box pressing machine, a box-supporting table, box lid pressing means mounted above said table, means operable at will for elevating and lowering said table including a driving member reciprocable in a vertical direction, a lever, means connecting one end of said lever to said table, means connecting the intermediate point of said lever to said driving member, a cam engaging the opposite end of said lever forming a fulcrum about which said lever rotates during a portion of the movement of said driving member and forming a slide bearing along which said lever slides during the remaining portion of the movement of said driving means.

7. In a box pressing machine, a box-supporting table, box lid pressing means mounted above said table, means operable at will for elevating and lowering said table including a driving member reciprocable in a vertical direction, a lever, means connecting one end of said lever to said table, means connecting the intermediate point of said lever to said driving member, a cam engaging the opposite end of said lever having a guide surface along which said lever may slide during portions of the movement of said driving member and having a notch extending from said guide surface to engage said lever to form a fulcrum about which said lever may rotate when moved by said driving member during another portion of the movement of said driving member, whereby a relatively small amount of movement of said driving member will cause a relatively great amount of movement of said box-supporting table as said lever is rotated and whereby said driving member will directly move said box-supporting table when said lever slides along said cam.

8. In a machine for applying covers to boxes, a box-supporting table for supporting boxes to

- be lidded, means on said machine above said table for pressing covers upon boxes, means on said machine for securing covers to boxes, and means operable at will to move said box-supporting table upwardly toward said pressing and lid-securing means, comprising vertically reciprocable means, lever means interconnecting said reciprocable means and said table, operable during the first portion of the upward movement of said moving means to move said table through a lever action and operable during the final upward movement of said moving means to transmit a direct upward thrust from said reciprocable means to said table.
- 10 9. In a machine for applying covers to boxes, a box-supporting table for supporting boxes to be lidded, means on said machine above said table for pressing covers upon boxes, means on said machine for securing covers to boxes, means operable at will to move said box-supporting table upwardly toward said pressing and lid-securing means, cylinder and piston means for lifting and lowering said table, lever means interconnecting said piston and cylinder means with said table to cause said table to be lifted through a relatively great distance upon initial
- 15 20 25

movement of said piston and cylinder means through a relatively small distance, and subsequently transmitting the thrust of said piston and cylinder means as a direct thrust, whereby a relatively short stroke produces a great travel of said table.

10. In a machine for applying covers to boxes, a box-supporting table for supporting boxes to be lidded, means on said machine above said table for pressing covers upon boxes, means on said machine for securing covers to boxes, means operable at will to move said box-supporting table upwardly toward said pressing and lid-securing means, cylinder and piston means for lifting and lowering said table, lever means interconnecting said piston and cylinder means with said table to cause said table to be lifted through a relatively great distance upon the initial movement of said piston and cylinder means through a relatively small distance, and for transmitting the thrust of said piston and cylinder means as a direct thrust during the final portions of the movement of said piston means, whereby a relatively short stroke produces a great travel of said table.

HERBERT E. TWOMLEY.
